CLAIM

The ornamental design for a combined container and slide tray for holding a compact disc, as shown and described.

DESCRIPTION

FIG. 1 is an exploded isometric view taken from the top, front and left side of a combined container and slide tray for holding a compact disc showing our new design and illustrated in a position of use;

FIG. 2 is a top plan view of the tray thereof;

FIG. 3 is a cross sectional view of the tray thereof taken along line 3—3 of FIG. 2;

FIG. 4 is a side elevational view of the tray thereof;

FIG. 5 is a bottom plan view of the tray thereof; and,

FIG. 6 is an isometric assembly view taken from the top, front and left side of the tray and container of FIG. 1 illustrated in another position of use.

The broken lines in FIG. 1 show environment only and form no part of the claimed design.

The bottom and right side of the container are mirror images of the top and left side thereof, respectively; the back of the container is unremarkable and devoid of any distinguishing feature.

The right side of the tray is a mirror image of the left side thereof.
